BY Owing & Rau ATTYS.

UNITED STATES PATENT OFFICE.

FRANK VOGELZANG, OF ROCK VALLEY, IOWA.

FUEL-PIPE LOCK DEVICE.

1,346,774.

Specification of Letters Patent. Patented July 13, 1920.

Application filed January 17, 1919. Serial No. 271,745.

To all whom it may concern:

Be it known that I, FRANK VOGELZANG, a citizen of the United States, and resident of Rock Valley, in the county of Sioux and 5 State of Iowa, have invented a certain new and useful Fuel-Pipe Lock Device, of which the following is a specification.

The object of my invention is to provide a fuel pipe lock device of simple, durable 0 and inexpensive construction.

A further object is to provide such a device which may comprise a series of telescoping valves arranged in a single valve casing, which casing is interposed in a fuel 5 line, the valve being provided with telescoping stems, the stems being provided at their outer ends with means whereby they can be rotated for setting the valves in any desired position.

0 The entire device is intended to be so constructed and arranged that when the valves have once been moved to inoperative position, it will be difficult for one not acquainted with their condition to set them 5 in condition for permitting fuel to pass through.

With these and other objects in view, my invention consists in the construction, arrangement and combination of the various 0 parts of the device, whereby the objects contemplated are attained, as hereinafter more fully set forth, pointed out in my claim and illustrated in the accompanying drawings, in which:

5 Figure 1 shows a vertical, sectional view through the floor of a motor vehicle equipped with a fuel line lock device embodying my invention.

Fig. 2 shows an enlarged, vertical central, sectional view through the valves.

Fig. 3 shows a top or plan view of the dials.

Fig. 4 shows a perspective view of the valve casing.

5 Fig. 5 shows a perspective view of one of the valve stems.

Fig. 6 shows a perspective view of the under surface of one of the dials.

Fig. 7 shows a top or plan view of the 0 cover cap for the dials, and

Fig. 8 shows a vertical, central, sectional view through said cover cap.

In the accompanying drawings I have used the reference numeral 10 to indicate 5 generally the floor of a motor vehicle having

the dash 11. Suitably located on the machine is a carbureter 12, which is supplied with fuel by a pipe 13.

Interposed in the fuel supply line is a cylindrical valve casing 14, which has opposite registering openings in its side walls. The valve casing is designed to be supported on the frame of the machine in any suitable way. Mounted within the valve casing 14 is a valve member 14^a having openings 15 and 16, which preferably register with each other and communicate with different portions of the fuel pipe line 13.

Received in and snugly fitting the interior of the valve member 14^a is a valve 17 having the form of a hollow cylinder. The valve 17 is provided with opposite openings 18, which register with each other and in one position of the valve register with the openings 15 and 16.

Received within the valve 17 and secured at its lower end to the valve member 14^a, is a cylindrical sleeve 19, having in its walls opposite openings 20 which register with the openings 15 and 16. It will be understood that the valve 17 is rotatable.

Received within the sleeve 19 is a rotatable valve 21, having in its walls opposite openings 22 designed in one position of the valve 21 to register with the openings 15 and 16.

Received within the valve 21 and secured at its lower end to the valve member 14^a, is a sleeve 23. The sleeve 23 is provided with openings 24 which register with the openings 15. Received within the sleeve 23 is a solid cylindrical valve 26, having an opening 27 which in one position of the valve 26 registers with the openings 15 and 16. The valve 26 has an upwardly extending stem 28.

The valve 21 has at its upper end a flange 29 extending inwardly and covering the upper end of the sleeve 23. At the inner edge of the flange 29 is an upwardly extending hollow stem 30, which terminates below the upper end of the stem 28.

The valve 17 has at its upper edge a similar inwardly extending flange 31, which rests partially upon the flange 29 and forms a cover for the sleeve 19. At the inner edge of the flange 31 is an upwardly extending stem having the form of a hollow sleeve 32, terminating below the upper end of the stem 30.

The valve stems hereinbefore described are 110

preferably projected upwardly through the floor 10 of the motor vehicle and through a suitable plate 33. The upper ends of the valve stems hereinbefore described are preferably angular in horizontal cross-section, as illustrated at 34 in Fig. 5.

Mounted on the upper ends of the valve stems 32, 30 and 28 are dials 35, 36 and 37, having hubs 38 provided with angular openings 39 to receive the angular ends 34 of the valve stems. The hubs 38 are locked to the valve stems by means of set screws 40.

It will be seen that by loosening the set screws the dial plates 35 may be set in different positions with relation to the stems and the valves. Each of the dials 35, 36 and 37 is provided with a series of indicating characters 41.

Suitably hinged to the plate 33 is a cover 42. The plate 33 and cover 42 are provided with coacting locking devices 43 and 44. Secured to the cover plate 33, near the hinge point of the cover 42, is an indicating finger 45 which extends upwardly and thence laterally above the dials 35, 36 and 37, for furnishing a means by which the various dials may be set.

In installing my improved device on a car, the valves may be placed in position and the plate 33 assembled, and thereafter the dials may be placed in position on the various valve stems while the valves are in open position. The then positions of the dials with relation to the indicator finger 45 may be ascertained, and the owner of the car will then know the combination; that is to say, will know the position in which the dials must be in order to set the valves at open position.

When the driver stops the car and desires to lock the fuel supply, he raises the cover 42 and turns any one of the dials. Any person who might desire to tamper with the car would not know which dial to turn first in order to move the valves to proper position

for permitting the passage of fuel through them.

It will be obvious that my device is of simple and inexpensive construction, and that it can be mounted as an attachment upon almost any type of motor car, and that it will serve efficiently to prevent strangers from starting the car.

Some changes may be made in the construction and arrangement of the various parts of my improved device without departing from the essential features and purposes of my invention, and it is my intention to cover by my claim any modified forms of structure or use of mechanical equivalents which may be reasonably included within their scope.

I claim as my invention:

In a device of the class described, a fuel line pipe, a valve casing included in said fuel line pipe having opposite registering openings communicating with said pipe, a plurality of spaced sleeves fixed together at their lower ends, said sleeves having a plurality of registering openings adapted to register with said first described openings, a plurality of valves adapted to be received between said sleeves and capable of rotation around said sleeves, said valves having openings adapted when in one position to form a passageway between the two pieces of fuel pipe and when in another position to close the passageway, flanges fixed to the upper ends of said valves, said flanges being adapted to overlap each other, telescoping stems fixed to said flanges, whereby rotation of the stems will rotate said valves, said casing having an inwardly extending flange designed to cover said first described flanges, thereby preventing the removal of said valves without first removing said casing, said valve casing being held in position by said fuel line pipe.

Des Moines, Iowa, November 22, 1918.

FRANK VOGELZANG.
